L. J. MUELLER

TOY

Filed Oct. 27, 1922

UNITED STATES PATENT OFFICE.

LEONARD J. MUELLER, OF DETROIT, MICHIGAN.

TOY.

Application filed October 27, 1922. Serial No. 597,239.

To all whom it may concern:

Be it known that I, LEONARD J. MUELLER, a citizen of the United States, residing at Detroit, in the county of Wayne and State 5 of Michigan, have invented a new and useful Improvement in a Toy, of which the following is a specification.

My invention relates to a new and useful improvement in a toy and has for its object 10 the provision of a toy which will be simple in structure, economical of manufacture and highly efficient in use.

Another object of the invention is the provision of a toy adapted for use as a roller coaster for marbles and the like and having means for preventing the marbles rolling thereon from reaching the lowermost incline of the coaster.

Another object of the invention is the 20 provision of an incline bearing member for the rolling of marbles and the like thereon and having reciprocating inclines which may be moved relatively to each other so that the marble rolling down an incline is 25 caused to roll onto an incline which was originally higher than the incline from which it passed.

Other objects will appear hereinafter.

The invention consists in the combinations and arrangements of parts hereinafter described and claimed.

The invention will be best understood from a reference to the accompanying drawings which form a part of this specification 35 and in which,

Fig. 1 is a side elevational view of the invention,

Fig. 2 is a sectional view taken on substantially line 2—2 of Fig. 1,

Fig. 3 is a sectional view taken on substantially line 3—3 of Fig. 1, and

Fig. 4 is a fragmentary plan view of the blank used in the invention.

The invention in its preferred form comprises a base 9 having upwardly projecting flanges 10 which serve as side-boards for the base upon which the marbles fall when they leave the incline. Projecting upwardly from the base member 9 are guide members 11 and 12, which are channel shaped and provided with flanges 15 and 16, the lower ends of said guides being fastened to the base by rivets or other suitable means. Connecting the upper ends of said guides is a cross member 13, the guides and said cross member being made from a stamping of

steel or tin. The cross member 13 is buckled at its center to form the upwardly extending portion 14, on the upper edge of which is pivotally mounted an arm or beam 31. 60

Positioned within the guides and adapted for slidable movement therein, within certain limits, is a pair of incline bearing members upon which marbles or the like may be placed to allow the same to roll down the 65 incline. These incline bearing members, in the present embodiment, are struck from a blank shown in Fig. 4. The sides 17 and 18 of the blank are turned at right angles to the main body of the blank. Struck from the main body of the blank are incline members 19, each incline being provided, intermediate its ends, with a recess 20, thus providing for a tongue 21 in the metal between 70

the inclines. As will be noted this tongue 75 extends longitudinally of the inclines and terminates within the ends of said inclines. Each of the inclines is provided with a tongue 22 and 23 at its opposite ends. It will be noted that these inclines are struck at an incline to the sides of the blank so that when the portion 19 is turned downwardly to form the platform or runway for the marbles rolling thereover, it will be inclined downwardly toward one side. When 80 the portion 19 is turned downwardly so that it extends at right angles to the plane of the main body of the blank the tongues 22 and 23 are thrust through slots 25 and 24, formed in the portions 17 and 18, and are 85 then turned over to bind the runway in operative position. It will be noted that the inclines are not extending at true right angles to the main body of the blank but are inclined bodily downwardly slightly, the 90 purpose of which will appear presently.

Positioned within the guides and extending centrally thereof is a spacing member 28, the upper end of which is angularly turned and secured by means of a suitable rivet 29 to the portion 13. The lower end thereof is also similarly turned and secured by means of a suitable bolt or screw to the base 9. As shown in Fig. 3 the spacer does not extend for the full width of the frame 100 formed by the guides and the cross member but terminates sufficient distance from the guides to permit the passage of a marble from one side thereof to the other. 105

In assembling the device the guides and cross member are erected on the base and the spacing member mounted thereon, the 110

incline bearing members being positioned within the guides, the portions 17 and 18 riding in the channels, the edges of said flanges 17 and 18 being extended inwardly 5 of the frame toward the spacer. When the incline bearing members are thus positioned the runways incline longitudinally in opposite directions and are inclined bodily, slightly, toward each other, so that a marble 10 or other spherical article placed thereon will run down the incline to the end of the runway. Having cleared the edge of the spacer the spherical article will then roll onto the incline on the opposite side of the 15 spacer and will then roll down this incline to the end thereof, so that a spherical article started at the top of the frame may roll down the several inclines to the bottom of the frame, being alternately at opposite 20 sides of the spacer.

The arm 31 is connected at one end by means of the member 32 to one of the inclined bearing members and at the other end by means of the member 33 to the other 25 incline bearing member. Provided in the flange 16 of one of the guides is a slot 26 in which rides a knob 27 which is mounted on one of the incline bearing members. By moving the knob vertically the incline bearing member is reciprocated in the guide and through the connection with the beam 31 the other incline bearing member is also reciprocated in the guides, these two members moving in opposite directions at the same 30 time. With this construction it is possible to raise the relative position of the sphere rolling down the inclines to the frame during the time the sphere is rolling. To illustrate this it may be supposed that a sphere 35 is rolling down the incline 77. This sphere will be deposited, at the end of the incline onto the runway 78. From this runway the sphere will pass onto the runway 79, if the runways are not moved. By moving the 40 knob downwardly the incline 78 is raised relatively to the runway 79, so that the sphere will be deposited on the runway 80 instead of the runway 79. By repeating this 45 action the sphere may be raised on the runways from the bottom to the top while it is still traveling downwardly on the various runways, the reciprocating of the incline bearing members being done quickly so that the change in position of these members 50 is brought about, each time, during the time it takes the sphere to travel the length of the runway.

It will be noted that the portion 21 extends upwardly at the outer edge of the 60 runway and serves as a guide to prevent the marble or sphere from rolling off the incline at its outer edge.

The spacer may be made from tin or it

may be made from some transparent material so the spheres rolling down the inclines or runways will be visible from either side of the device. 65

While I have illustrated and described the preferred form of construction I do not wish to limit myself to the precise form of structure shown but desire to avail myself of such variations and modifications as come within the scope of the appended claims. 70

Having thus described my invention what I claim as new and desire to secure by Letters Patent is:

1. A toy of the class described comprising a frame; a spacing element mounted in said frame; a set of runways slidably mounted in said frame on opposite sides of said element; and means for changing the relative position of said sets. 80

2. A toy of the class described comprising a frame; separate runway bearing members mounted in said frame; runways mounted in each of said bearing members, said runways being longitudinally and transversely inclined to the vertical, the runways in the separate bearing members being co-operatively arranged and transversely inclined toward each other, for permitting the reception by the runway of one bearing member of a rolling member traveling on a runway in the other bearing member; and means for changing the relative position of said bearing members. 90 95

3. A toy of the class described comprising a supporting member; runway bearing members associated with said supporting members and movable vertically relatively thereto; runways mounted in said bearing members inclined longitudinally and transversely to the vertical; a spacing element mounted on said frame and adapted for separating the runways of the separate bearing members intermediate their ends; and a rocking beam associated with said bearing members for effecting a reciprocation of the same. 100 105

4. A toy of the class described, comprising a supporting member; a pair of sets of runways, oppositely disposed, each runway being longitudinally inclined to the vertical, the runways in one set being adapted for the reception of a rolling object from the co-operating runways of the other set, said sets being relatively movable for permitting the bodily movement of the runways in one set to a position above or below co-operating runways in the opposite set, the runways in said sets being co-operative in either position. 110 115 120

In testimony whereof I have hereunto set my hand at Detroit in the county of Wayne and State of Michigan.

LEONARD J. MUELLER.
